UNITED STATES PATENT OFFICE.

VINCENT BURDI, OF NEW YORK, N. Y.

MECHANICAL TOY VEHICLE.

Application filed September 12, 1923. Serial No. 662,191.

To all whom it may concern:

Be it known that I, VINCENT BURDI, a subject of the King of Italy, and resident of the borough of Bronx, county of Bronx, city and State of New York, have invented certain new and useful Improvements in Mechanical Toy Vehicles, of which the following is the specification.

The device, the subject of this invention 10 is a toy vehicle, shaped as a hobby horse, adapted to carry a rider and propelled by the rider with approximately the same motion as is obtained by rowing.

The device then serves, not only as a 15 means of locomotion, but also as a means of obtaining and promoting exercise of practically all parts of the body.

A principal object of the invention then, 20 may be considered that of promoting exercise and making the exercise attractive.

Another object of the invention is to produce a device of the nature set forth, that will not only be simple in construction and operation, but will be so constructed and 25 designed that there will be the fewest possible number of parts and all of the parts will be so designed and proportioned that even should they become worn or broken, replacements or repairs may be readily 30 made at a minimum of expense.

The following is what I consider the best 35 means of carrying out this invention and the accompanying drawings should be referred to for a complete understanding of the specification which follows.

In the drawings:—

Fig. 1, shows the device in operation.

Fig. 2, is an enlarged detail, partly in 40 section and shows the driving mechanism.

Fig. 3, is a longitudinal, sectional view, the section being taken approximately upon the central line through the device.

Fig. 4, is a sectional view on the line 4—4 45 of Fig. 3 of the driving mechanism and the tractor wheel mountings.

Fig. 5, is a view in elevation, partly in 50 section, of the steering mechanism.

Fig. 6, is a perspective view upon an enlarged scale and shows a lever construction.

Similar reference numerals indicate like 55 parts in all the figures where they appear.

At 1, I show the body of the device which I prefer should be shaped as an animal and in the drawings, I have shown a figure of a horse, with the legs 2 and 3 extended, as in

running. The figure should be provided with a saddle 4 and a head stall or bridle 5, of which a member having the appearance of a bit, but which I will refer to as a lever device, forms a part.

The figure 1, is supported upon a plurality of wheels of which there should be three as indicated at 6, 7 and 8. The wheel 8 is of smaller diameter than the wheels 6 and 7 and while the wheels 6 and 7 are outside 65 of the line of the figure, the wheel 8 may be directly under the body of the figure.

The wheel 8 is supported upon the stem 9, which may be curved inward as shown 70 at 10 and the stem 9 is pivotally supported in a bracket 11 and upon a member 12, adjacent to which a flange 13 is arranged, the flange being secured upon the stem 9.

Projecting through the stem 9 and at a point adjacent to the forked and curved 75 member 10, is a shaft or pin 14, provided with foot rests as shown at 15 and 16, adapted to receive the feet of the operator and by pressing forward either foot rest, the position of the wheel 8 is changed and 80 the course of the vehicle controlled.

Extending through the back legs of the figure and through thimbles or bearing members 17 and 18, secured therein, is a shaft 19 upon which is secured the hubs 20 85 and 21 of the wheels 6 and 7. The hubs may be secured by means of pins, one of which is shown at 22 and nuts 23 and 24 may also be provided, to prevent the displacement of the wheels.

Upon the shaft 19 and approximately midlength thereof, I secure a ratchet or driving member as shown in Figs. 2 and 4. The driving member consists of a ratchet wheel 25 secured to the shaft 19 by a spline 90 or key 26 or by any other suitable means, the ratchet wheel 25 being provided with any desired number of teeth.

Exterior of the ratchet wheel 25 is a drum 100 formed of two parts, 27 and 28, the parts being secured together in any suitable manner and loosely mounted upon the shaft. The drum is provided with a cable groove 29 in which is secured the flexible member 46 which will again be referred to.

Each section, 27 and 28 of the drum member is provided with a hub portion as shown at 30 and 31, the hub portions being rotatably mounted upon the shaft 19 and free to move thereon as required. The hubs may 105 110

be retained in proper position by collars as shown at 32 and 33, the collars being pinned or otherwise secured to the shaft 19.

Within the drum and pivoted therein is 5 a ratchet or pawl 34, retained in flexible engagement with the ratchet wheel 25 by means of a spring 35. A rather long and strong spring 36, has one of its ends secured in the periphery of the drum, and its other ends permanently secured to the under part of the figure as indicated at 37.

The cable 46 extends through the body of the figure, from an idler wheel 38, arranged at a convenient place, probably in the neck 15 of the figure and is secured to the upwardly projecting member 39 of the lever mechanism, before referred to and now described in detail.

The bar 40 of the lever member extends 20 through the mouth of the figure and at each end of the bar 40, depending links 41 and 42 are secured. The flexible members 43 and 44 having the appearance of driving reins are secured, one to each of the depending members 41 and 42.

The operation of the device can be understood from Fig. 1 and is as follows:—

The rider straddling the figure, places one foot upon each of the foot rests 15 and 16 and grasping the reins 43 and 44 in the hands, pulls the reins backward by a movement of the arms or body or both and thereupon the members 41 and 42 are pulled backward, and the member 39 moved forward as the shaft 40 is partially rotated. The flexible member 46 partially rotates the drum 27—28, the pawl 34 engaging a tooth of the ratchet wheel 25, partially rotates this wheel and the shaft 19 and wheels 6 35 and 7.

When the full extent of the backward motion is urged, the rider moves the arms and body or both the arms and body forward allowing the spring 36 to return the

drum 27—28 to their original position, taking up the flexible member 46 and partially rotating the shaft 40 and the links attached thereto, whereupon a repetition of the backward movement of the rider will again partially rotate the traction wheels 6 and 7. 50 The steering of the device is accomplished in the manner previously described.

As before stated, the body of the device may be made to simulate any animal, and it may be made of any size. A stop 45 may be 55 provided to limit the movement of the shaft 40 and other modifications may be made within the scope of the appended claim, without departing from the principle or sacrificing the advantages of the invention. 60

Having carefully and fully described my invention, what I claim and desire to obtain is:—

A mechanical toy vehicle comprising a figure simulating an animal, traction wheels 65 having a shaft extending through the legs of said figure at a point adjacent the body thereof, a steering wheel of smaller diameter than said traction wheels and arranged under the body of said figure and between 70 though independent of the legs thereof and having a supporting pin entering the body of said figure, a bar connected to the steering wheel and having foot rests thereon, means for rotating the traction wheels, 75 said means comprising a drum on said shaft, a pawl and ratchet wheel within said drum, a flexible member upon said drum, resilient means connected to said drum for operating it in one direction, a second shaft journaled in the figure, arms on the second shaft, a plurality of flexible members secured to the arms for use by the rider in imparting motion to the drum, and a flexible connection between the second shaft and the drum. 80

Signed at the city, county and State of New York, this 28 day of August, 1923.

VINCENT BURDI.
